DESIGN FOR A DRESS ENSEMBLE

Marie Pono, New York, N. Y.

Application December 3, 1937, Serial No. 73,330

Term of patent 3½ years

To all whom it may concern:

Be it known that I, Marie Pono, a citizen of the United States of America, residing in city of New York, county of New York, and State of New York, have invented a new, original, and ornamental Design for Dress Ensemble, of which the following is a specification, reference being had to the accompanying drawing, forming part thereof.

Fig. 1 is a front view of a dress ensemble showing my new design.

Fig. 2 is a front view of the dress member of the ensemble.

Fig. 3 is a rear view of Fig. 2.

Fig. 4 is a rear view of the jacket portion of the dress ensemble.

My design is characterized by the specific embroidery on the jacket and waist portion of the dress as shown.

I claim:

The ornamental design for a dress ensemble, substantially as shown and described.

MARIE PONO.
